UNITED STATES PATENT OFFICE

2,432,754

VEHICLE EXTERIOR LIGHTING UNIT

Eric B. Hallman, Philadelphia, Pa., assignor to
 Electric Service Manufacturing Company,
 Philadelphia, Pa., a corporation of Pennsylvania

Application August 25, 1945, Serial No. 612,624

1 Claim. (Cl. 240—7.45)

1

This invention relates generally to external lighting fixtures for automotive vehicles and more particularly to an improved construction of auxiliary dash floodlighting fixture adapted for use in illuminating not only the front dash of the vehicle, such as a street railway car, bus or the like, but also the ground directly in front and to either side of the dash of the vehicle.

Among the principal objects of the present invention is to provide a lamp housing for the lighting fixture which is completely water-proof and weather-tight and which includes easily manipulated means for effecting ready removal of the lamp hood for renewal of the lamps and for general maintenance and repair of the fixture.

A further and important object is to provide a novel means for detachably securing the lamp hood to its supporting base, said means being operative to insure such a tight, water-proof fit of the hood against its supporting base as to effectually seal the interior of the fixture against the deleterious effects of inclement weather and the like.

Other objects and advantages of the invention will appear more fully hereinafter, it being understood that the present invention consists substantially in the combination, construction, location and relative arrangement of parts, all as described in detail hereinafter, as shown in the accompanying drawings and as finally pointed out in the appended claim. In the said accompanying drawings,

Figure 1 is a front elevational view of the lighting fixture as constructed in accordance with and embodying the principles of the present invention;

Figure 2 is a side elevational view thereof;

Figure 3 is a top plan view of the base member and lamp reflector assembly, with the hood removed therefrom;

Figure 4 is a transverse sectional view of the complete fixture as taken along a line corresponding to line 4—4 of Figure 3;

Figure 5 is a rear elevational view of the base of the fixture;

Figure 6 is a longitudinal sectional view of the base and lamp reflector assembly as taken along the line 6—6 of Figure 5; and

Figure 7 is a sectional view of said assembly as taken along the line 7—7 of Figure 5.

Referring now to the drawings and more particularly to Figure 1, 2 and 4 thereof, it will be observed that the lighting fixture of the present invention essentially includes a base assembly 10 and a hood assembly 11 which are adapted to be secured together in the manner and by the means hereinafter to be described to provide a hermetically sealed housing for the lamps 12.

The base assembly 10 includes a substantially flat base plate 13 of generally rectangular form, the longitudinal side edges of which are folded

2

over upon themselves, as at 14, to strengthen and rigidify the said plate 13. Overlying the plate 13 is a soft rubber gasket 15 having a marginal flange 16 completely surrounding the perimetral edges of the base. This gasket 15 is centrally provided with an integrally formed tubular hub 17 which projects through a central opening 18 formed in the plate 13, the electrical conducting wires leading to the lamp sockets being projected through the bore of said hub 17. In addition, this gasket member 15 is provided on its outer flat surface with a raised rib 19 spaced inwardly from the outer edge of the gasket and extending perimetral thereabout to provide a substantially rectangular shouldered seat 20 for reception of the hood assembly 11 (see Figure 4).

Disposed flatwise against the outer surface of the gasket 15 is a supporting member 21 for the lamp reflector 22 and its associated lamp sockets 23. This supporting member 21 essentially consists of a flat plate of generally rectangular form, the opposite longitudinal edges of which are respectively turned to provide a pair of flanges 24 and 25 (see Figure 4), these flanges 24 and 25 being each provided with a pair of longitudinally spaced depressions 26—26. It will be noted that these depressions 26—26 are each provided with inclined surfaces 27 in the portions thereof immediately adjacent the plate 21 for a purpose which will be observed hereinafter. Also, it will be noted that the side flanges 24 and 25 of the supporting member 21 are each provided with inturned flanges 28, which rests flatwise against the outer surface of the gasket 15. The supporting member 21 is secured in its position shown in Figure 4 by means of a pair of screws 29—29 (see Figure 6), which project through apertures suitably provided therefor in the main plate 21 of said supporting member for threaded engagement with the base plate 13, the gasket 15 being provided with apertures to permit the free projection of the screws 29—29 therethrough. These screws 29—29 thus serve to secure the base plate 13 and the supporting member 21 together with the gasket 15 interposed therebetween.

The reflector 22 forming part of the base assembly is readily secured to the supporting member 21 in any suitable manner. It will be noted that this reflector member 22 is in the form of a simple sheet metal stamping having a flat supporting portion 30 and a reflector portion 31 of the arcuate shape shown in the drawing. Preferably, support 21 for the reflector is provided with a series of longitudinally spaced, raised, 55 knob-like projections 32 which are spot welded to the flat portion 30 of the reflector, while the lamp sockets 23 are rigidly and permanently secured in any suitable manner to the reflector, preferably as by spinning the flange elements 33 of the sockets 23 against the body of the reflector 22. In the unit as shown, the reflector is pro-

vided with three lamp sockets longitudinally spaced apart, as shown, these lamp sockets being each projected through suitable apertures formed in the reflector with the flange elements 33 of the sockets spun over the edges of the apertures, as shown most clearly in Figure 4. The reflector 22, its support 21, the gasket 15 and the base plate 13 thus constitute a unitary base assembly for the lighting fixture, which is adapted to be mounted upon the front dash of the vehicle by means of four bolts 34—34 which are each carried by sheet metal elements 35 permanently secured, as by welding to the rear face of the base plate 13. These elements 35 are of wing-like form and may be adjusted toward or away from the base plate 13 of the base assembly as the surface contour of the mounting surface may require, thereby insuring a proper fit of the lighting unit against the front dash surface of the vehicle. The perimetral flanges 16 of the gasket constitute a resilient cushion between the dash and the lighting fixture and serve to absorb vibrations and shocks which might tend to adversely affect the operating life and efficiency of the unit.

The hood assembly 11 essentially consists of a sheet metal casting 36 of a shape and form best shown in Figures 1, 2 and 4. This casting 36 is provided with substantially flat top wall 37 inclined downwardly and forwardly with respect to the vertical plane of the gasket 15. This top wall terminates along its front edge in a rounded portion 38 and at its opposite side ends in rounded portions 39—39 which are joined together by a bottom member 40 formed as an integral part of the hood casing. This bottom member 40 is, however, of considerable radius width as compared with the overall width of the hood so as to provide an elongated opening 41 in the frontal bottom part of the hood, as appears most clearly in Figure 4. This bottom opening is extended rearwardly on either side of the hood to provide lateral side extensions 42 of the opening, the opening being fitted with an enclosure glass 43 of a shape suitably complementary to that of the hood opening 41. The rear edge 44 of the glass enclosure rests upon the bottom member 40 of the hood casting 36, while the upper edge portion 45 of the enclosure rests against that portion of the hood casting 36 which defines the upper marginal edge of the window opening 41. The glass enclosure is secured rigidly in position by means of a clamping plate 46, which is suitably secured by screws or the like (not shown) to the bottom member 40 of the hood casting 36.

The rear perimetral edges of the hood casting 36 are disposed in a vertical plane and are adapted to be singularly seated against the shoulder seat 20 formed externally of the rib 19 in the gasket 15. In order to secure the hood assembly to the base assembly, the hood casting 36 is provided in its top portion 37 with a pair of spaced internal projections 47 adapted respectively for seating engagement within the spaced depressions formed in the top flange 25 of the reflector and lamp socket supporting member 21. The bottom member 40 of the hood casting 36 is fitted with a pair of similarly spaced securing screws 48 which are adapted for respective engagement within the depressions 27—27 formed in the bottom flange 24 of the supporting member 21. It will be noted that the fixed internal projections 47 in the top of the hood casting 36 engage the inclined portions 27 of the upper depressions 26—26, while the inner ends of the se-

curing screws 48 similarly engage the inclined portions 27 of the bottom depressions 26—26. In consequence of this, it will be apparent that upon tightening the screws 48 the internal projections 47 and the said screws 48 will so act in conjunction with the inclined surfaces which they respectively engage to cam the hood assembly into such close and secure engagement with the gasket 15 as to effect a hermetic seal therebetween, thereby rendering the interior of the housing completely weather tight and waterproof.

When the lighting unit of the present invention is properly mounted upon the front dash of the vehicle, the light rays emanating from the several lamps will be directed through the glass enclosure 43 in a direction generally downwardly and forwardly of the vehicle, as well as downwardly and laterally to either side thereof. The lighting fixture of the present invention is thereby of distinct help at night to distinguish the vehicle from various other vehicles, to indicate the width of the vehicle and to light that portion of the street or platform where passengers may stand prior to boarding the car.

It will be understood, of course, that the present invention is susceptible of various changes and modifications which may be made from time to time without departing from the real spirit or principles thereof, and it is accordingly intended to claim same broadly, as well as specifically, as indicated in the appended claim.

What is claimed as new and useful is:

A vehicle front dash lighting unit comprising, in combination, a rigid substantially rectangular mounting for a lamp socket and reflector assembly, said mounting having flanges extending rearwardly from its top and bottom edges, a resilient pad disposed flatwise against the rear edges of said mounting flanges, said pad having a marginal portion extending freely beyond the perimetral edge of said mounting and said marginal portion of said pad being provided with a perimetral continuous rearwardly extending resilient flange, a housing for said lamp socket and reflector assembly adapted to be fitted over said mounting with its rear edges in engagement with said freely extending marginal portion of the pad, coacting camming elements respectively provided in said mounting and housing operative to force the rear edges of the latter into closely fitting engagement with said pad to provide a hermetically sealed enclosure for said lamp socket and reflector assembly, and means disposed interiorly of the flanged portion of the pad for securing the unit against a fixed support with the flanged portion of the pad in engagement with the surface of said support, said flanged portion of the pad thereby constituting a resilient cushion between the unit and the surface against which it is secured.
